STOCK ANCHOR FOR SNAGLESS CONTINUOUS STOCK REELING OPERATIONS

Benjamin H. Davis, Noank, Conn., assignor to The Standard Machinery Company, Mystic, Conn., a corporation of Connecticut

Application April 3, 1956, Serial No. 575,909

21 Claims. (Cl. 242—25)

This invention relates to continuous multi-reel winding apparatus in general, and to multi-reel apparatus of a continuous snagless stock-winding type in particular.

Reel-winding apparatus of the kind to which the present invention generally relates commonly hold two adjacent reels of which one reel is driven and fully wound with flexible stock from a continuous supply under the control of a guide which moves back and forth widthwise of the reel to lead the stock onto the latter in successive layers of orderly arranged turns, whereupon the winding of the stock is without interruption continued on the adjacent second reel by quickly shifting the guide into operative relation therewith to continue its back and forth motion for the same orderly deposit of stock on the second reel. In thus quickly shifting the guide into operative relation with the second reel while both reels are driven, the guided stock is compelled to cross over the adjacent end rims of the reels and, in consequence, start its wind on the second reel. As soon as the stock is securely anchored to the second reel, a knife will sever the cross-over stock length between the reels. The drive of the full reel is thereupon discontinued and the latter is removed from the apparatus and replaced by an empty reel while the winding of stock on the second reel continues uninterruptedly. When the second reel has been fully wound with stock, the guide is quickly shifted into operative relation with the adjacent replaced empty reel which at that time is also driven, thereby compelling the guided stock to cross over from the second reel to the empty reel and start its wind on the latter, the knife again severing the crossover stock between both reels and thereby releasing the second, full reel for replacement in the apparatus by another empty reel. The stock-winding operation thus continues uninterruptedly and reels in the apparatus are successively wound with stock and replaced by empty reels to be wound with stock, in the foregoing fashion, until the apparatus is stopped or the continuous supply stock is exhausted.

For releasable anchorage of the severed ends of the crossover stock to the respective reels, recourse has hitherto been had to known snaggers of the stock-wedging type. These prior snaggers are arranged on the outside of the adjacent end rims of reels in the winding apparatus, each being essentially a disc with spaced peripheral elements which form with the adjacent peripheral edge of the disc wedge-shaped notches that are open in the normal drive direction of the reels. Thus, on crossover of the stock from one reel to the other while both reels are driven, the peripheral elements on the snaggers nearest the crossover stock will engage and quickly deflect the latter into the associated notches wherein the same will become firmly wedged and thus anchored to the snaggers. Accordingly, on subsequently severing the crossover stock between the two reels, the severed end thereof, which is anchored to the snagger on and constitutes the trailing stock end of the full reel, is prevented from acting as a potentially damaging and hazardous whirling snag end until the full reel is brought to a stop, while the other

2

severed end of the crossover stock, which is anchored to the snagger on and constitutes the leading stock end for the adjacent empty reel, is held out of the latter and constitutes the anchored end of the stock for its wind onto the empty reel.

While these prior snaggers of the stock-wedging type are satisfactory for many stock-winding operations, they are not so satisfactory, and are even unsuited, for other stock-winding operations involving high winding speeds or the winding of lighter and more readily tearable stocks, or both. This is due to the fact that snaggers of the stock-wedging type are inherently rather severe on the stock, involving not only rather high compressive stresses in short stock lengths but, more importantly, also quite sudden and severe bending of the stock thereat, wherefore the stock is at its very anchorage to the snaggers subjected to maximum stresses which are considerably higher than those induced in the stock during its wind on a reel. Also, the prior snaggers of the stock-wedging type require a very fast shift of the stock guide for crossing the stock from one reel to the adjacent reel in order to anchor the stock to the snaggers on both reels during less than one revolution of the latter and thus prevent hopeless entanglement of the stock in the winder or even snapping of the same. This imperative requirement of a very fast crossover shift of the stock guide so that the snaggers on both reels catch the crossover stock almost simultaneously poses a problem in most winders, and poses a particularly difficult problem in modern winders in which the winding and also the crossover motions of the stock guide are caused advantageously by a driven screw-type spindle.

It is the primary aim and object of the present invention to provide winding apparatus of the aforementioned kind in which the crossover stock between two reels is secured to snaggers or anchor discs thereon, not by being wedged thereto as heretofore, but rather by being wound thereon, thereby not only obviating the aforementioned severe treatment of crossover stock by the prior snaggers and offering greater assurance for the secure anchorage of the stock to the snaggers, especially at higher winding speeds or if the stock is of a lighter or more readily tearable kind, or both, but also permitting a crossover shift of the stock guide from one reel to the next reel at a slower rate than was permissible with these prior snaggers, and even at a rate at which its winding as well as crossover motions may readily be derived from a driven screw-type spindle.

It is another object of the present invention to provide the aforementioned anchor discs on adjacent reels in the winding apparatus with stock wind-on rims, and also with peripheral tracks which are in wind-on relation with successive lengths of the crossover stock and lead the wound-on stock onto the respective rims, thereby placing the wind-on stock onto the anchor discs under the control of the tracks on the latter and not under the control of the crossing-over stock guide, and thus permitting the secure anchorage of the crossover stock to the anchor discs by wind-on in the first place.

It is a further object of the present invention to construct each of the aforementioned anchor discs so that the stock wound thereon will, after severance of the crossover stock, remain securely anchored thereto even if the stock is so unwieldy that the wound length thereof would ordinarily not stay wound on the anchor disc of its own accord but would, instead, unwind at least sufficiently to lose its anchorage thereon or act as a potentially dangerous and damaging snag. To this end, each anchor disc has provisions for effectively counteracting any and all unwinding tendencies of even the most unwieldy stock wound thereon.

Other objects and advantages will appear to those

skilled in the art from the following, considered in conjunction with the accompanying drawings.

In the accompanying drawings in which certain modes of carrying out the present invention are shown for illustrative purposes:

Fig. 1 is a front view of stock-winding apparatus in which are mounted stock anchors embodying the present invention;

Fig. 11 is a fragmentary section through a reel and stock anchor unit embodying the present invention in a further modified manner; and

Fig. 12 is a fragmentary section taken substantially on the line 12—12 of Fig. 11.

Referring to the drawings, and more particularly to Figs. 1 and 2 thereof, the reference numeral 20 designates a continuous stock winding apparatus which in all essentials is, or may be, like the winding apparatus disclosed in the copending application of Nelson et al., Serial No. 565,636, filed February 15, 1956. Thus, the instant winding apparatus comprises a main frame 22 which carries the various operating devices of the apparatus. The main frame 22 comprises, in the present instance, opposite end brackets or castings 24 and 26 which are joined by parallel tie rods or bars 28 a—e and angles 30 and 32. The various operating devices of the apparatus are reel stands 36, stand operating devices 38, reel drives 40, a stock guide 42, guide operating means 44, stock severing means 46, and stock anchors 48.

The present apparatus comprises two stands 36, each for removably supporting a rotary reel R for winding continuous stock s thereon. Reels on the stands 36 are successively wound with stock, and each full reel is replaced by an empty reel while the other reel is being wound with stock. Each stand is also shiftable into reel-winding and reel-exchange positions in which a reel thereon is free to turn above the floor or another support and is lowered thereonto for replacement by an empty reel. Since both stands are identical in their construction and performance, except that they are of left and right hand design (Fig. 1), only one of these stands, namely the stand 36A, will be described in detail. Thus, the stand 36A, which is preferably a casting, has opposite sidewalls 52 and a connecting front web 54 of which the lower ends of the sidewalls 52 terminate in spaced lugs or prongs 56 that are axially slidable and turnable on the foremost tie or frame bar 28a near the bottom of the frame. The stand 36A is thus swingable on the frame bar 28a into the upright reel-winding position shown in Figs. 1 and 2, and also into a forwardly inclined reel-exchange position (not shown) in which a fully-wound reel thereon rests with its end flanges r on the floor or another support for exchange with an empty reel in a manner to be described. The upper ends of the sidewalls 52 of the stand 36A terminate in rearwardly extended bearing lugs 58 holding antifriction bear-

ings 60 (Fig. 3) in which a drive sleeve 62 is journaled. The bearings 60 are kept lubricated by grease G from adjacent seal rings 64 of any suitable type, the grease supply therein being replenished from time to time through nipples 66 on and ducts 68 in the bearing lugs 58. Keyed at 70 to the drive sleeve 62 is a pulley or sheave 72 which extends between the bearing lugs 58 of the stand. Axially slidable in the drive sleeve 62 is a reel spindle 74 which extends beyond the right side of the stand 36A, as viewed in Figs. 1 and 3, for removably supporting a reel R thereon. The reel spindle 74 may in any of an infinite number of axially adjusted positions in the sleeve 62 be locked to the latter for rotation therewith and against axial movement relative thereto. To this end, there is provided a collet 76 (Fig. 3) having longitudinally slit tapered jaws 78 which cooperate with a diametrically enlarged and tapered end 80 of the bore 82 in the sleeve 62 in which the reel spindle 74 is slidably received. The collet 76 has a head 84 carrying bolts 86 which are threadedly received in the sleeve 62. Thus, the collet 76 will become firmly clamped to the sleeve 62 and to the reel spindle 74 when the bolts 86 are tightened. Conversely, on loosening the bolts 86, the collet 76 will release the reel spindle 74 for axial adjustment in the sleeve 62 as well as for retraction thereinto of the projecting reel-supporting length of the spindle 74 for reel-exchange purposes as described hereinafter. Keyed at 88 to the drive sleeve 62 is a coupling member 90 carrying a preferably radially adjustable pin 92 adapted to be received in a coupling aperture in the adjacent end flange r of a reel R on the spindle 74. The reel is thus releasably drivingly connected with the sleeve 62 and sheave 72 thereon through intermediation of the coupling member 90. Furthermore, the reel is retained axially on the spindle 74 and also in coupling relation with the pin 92 by means of a removable end collar 94 on the spindle. The end collar 94 is to this end provided with a transverse bore 95 in which is slidable a plunger 96 that is normally urged by a spring 97 into the lock position shown in Fig. 6 in which the same is in interlock with a peripheral groove 99 in the adjacent end of the reel spindle 74 and thus holds the end collar 94 fast on the latter. In order to release the end collar 94 for removal from the reel spindle 74, the plunger 96 is retracted, against the compression of the spring 97, until a peripherally recessed portion 101 of the plunger aligns with the spindle 74 and thereby releases the former from interlock with the latter for axial removal of the end collar. The plunger 96 is to this end provided on its reduced shank 103 with a suitable knob 105.

For replacing a full reel on the spindle 74 of the stand 36A with an empty reel, the stand is first swung about the frame bar 28a, by power means to be described, into the aforementioned reel-exchange position in which the full reel rests on the ground, for instance. Next, the collet 76 (Fig. 3) is released from the spindle 74 and the end collar 94 removed from the latter, whereupon the spindle is retracted into the drive sleeve 62, to the left as viewed in Figs. 1 and 3, sufficiently to clear the reel. The full reel may now be rolled away and an empty reel rolled in place thereof, whereupon the spindle 74 is projected into and through the empty reel sufficiently to permit reattachment of the end collar 94 to the spindle adjacent the end rim r' of the empty reel, subject to interposition therebetween of one of the stock anchors 48 to be described. On subsequently reclamping the collet 76 to the spindle 74, the stand may, by the aforementioned power means, be swung into its winding position (Figs. 1 and 2) for a stock winding operation on the reel thereon.

The stand 36A may be locked to the frame bar 28a against axial movement from any one of an infinite number of axially adjusted positions thereon. To this end, there is provided an anchor bracket 98 which is axially slidable on the adjacent frame bars 28a and 28b and fittedly straddled by the bottom lugs 56 of the stand 36A (Fig. 1) so that the latter is slidable on the frame

bar 28a in unison with the anchor bracket 98. The anchor bracket 98 is, in the present instance, provided with a jaw element 100 which, on tightening and loosening a screw 102 in threaded engagement with the anchor bracket, is forced into and released from clamping engagement, respectively, with the frame bar 28a, thereby locking the anchor bracket to the frame bar 28a in any axially adjusted position thereon and releasing the same therefrom for axial adjustment thereon, respectively. Thus, the stand 36A may be axially adjusted on the frame bar 28a in unison with the anchor bracket 98, and will become locked against movement from any axially adjusted position while retaining its freedom to swing on the frame bar 28a, on locking the anchor bracket 98 to the latter.

The power drive of a reel on the stand 36A commences and terminates on swinging the latter into and from its upright winding position, respectively, in which the sheave 72 is in driving relation with the associated reel drive 40A to be described. In order to avoid free-wheeling of a fully-wound reel on swinging the stand 36A from its winding position toward its exchange position, and especially when the reel comes to rest on the floor or another support, the stand is provided with an automatic reel brake 104 (Fig. 2) in the form of an arm which is pivoted at 106 to the sidewalls 52 of the stand and extends therebetween, and is provided with a shoe 108 of rib-like formations that engage in the peripheral grooves 110 in the sheave 72 (Fig. 1) and apply a brake force to the latter, and hence to the reel coupled thereto, when the shoe 108 is in its brake position (not shown). The shoe 108 is normally urged into its brake position by a spring or springs 112 which connect the brake arm 104 with the bearing lugs 58 of the stand. The reel brake is rendered automatic in its action by virtue of the provision of an upstanding lug 114 on the anchor bracket 98 which is engaged by the lower end of the brake arm 104, and hence causes the same to shift out of braking relation with the sheave 72, when the stand is swung into its winding position (Fig. 2), and which releases the brake arm for spring-return into braking relation with the sheave 72 when the stand is swung from its winding position toward its exchange position, as will be readily understood. The reel brake is thus released from the sheave 72 every time the stand is swung into its winding position for immediate resumption of the power drive of a reel thereon, and is effectively applied to the sheave 72 whenever the stand is swung toward its exchange position so as to stop free-wheeling of a fully-wound reel thereon in any event before the same is lowered onto the floor.

As already mentioned, the other reel stand 36B (Fig. 1) is in all respects identical with the described reel stand 36A, except that the stands are of left and right hand design. Thus, while the reel-coupling member 90 and the reel-carrying projection of the spindle 74 are on the right side of the stand 36A as viewed in Fig. 1, the reel-coupling member 90b and the reel-carrying projection of the spindle 74b on the stand 36B are on the left side of the latter as viewed in the same Fig. 1. Certain prominent parts of the reel stand 36B are identified in the drawings by the same reference numerals as their counterparts of the stand 36A, except that the suffix "b" is added thereto.

Since the operating devices 38 of both stands 36A and 36B are identical, only one of them will be described in detail, namely the device 38A which is associated with the stand 36A (Figs. 1 and 2). Thus, the device 38A comprises a cylinder 120 and a piston therein having a rod which is pivotally connected at 126 to rearwardly projecting ears 128 in one of the bearing lugs 58 of the stand, while the cylinder 120 is pivotally connected with the main frame 22. To the latter end, the cylinder 120 is provided intermediate its ends with a fixed collar 130 having diametrically opposite trunnions 132 swivelled

in bars 134 that are bolted or otherwise secured at 136 to the opposite sides of a mounting bracket 138 which is freely slidable on the frame bars 28c and 28d. In thus pivotally supporting the cylinder 120 with its center of gravity near the collar 130 thereon, the same is more or less balanced regardless of the position of the piston therein.

In the present instance, the piston in the cylinder 120 is double-acting, wherefore the latter is provided at both ends 140 and 141 thereof (Fig. 3) with fluid admission and discharge ports (not shown) that communicate with a suitable valve (not shown) which is operable, preferably manually under the control of an operator, to admit fluid under pressure, such as compressed air, for instance, into either cylinder end 140 or 141 and simultaneously vent the other cylinder end. Thus, on admitting fluid under pressure into the cylinder end 140 and venting the other cylinder end 141, the stand 36A is swung into its winding position (Figs. 1 and 2) in which the ears 128 on the stand 36A are held against the adjacent end of the cylinder 120 by the piston therein. Conversely, on admitting fluid under pressure into the end 141 of the cylinder and simultaneously venting the other end 140 thereof, the stand 36A will be swung into its exchange position.

Since the mounting bracket 138 of the stand-operating device 38A is axially slidable on the frame bars 28c and 28d, as described, it stands to reason that the device 38A is axially adjustable in unison with the associated reel stand 36A. As already mentioned, the operating device 38B, which is associated with the reel stand 36B, is in all respects identical with the described stand-operating device 38A. Prominent parts of the stand-operating device 38B are identified in Fig. 1 by the same reference numerals as their counterparts of the described operating device 38A, except that the suffix "b" is added thereto.

The reel drives 40A and 40B, which are associated with the reel stands 36A and 36B, respectively, are identical in every respect, wherefore only one of these reel drives, namely the drive 40A, will be described in detail. Before proceeding with the detailed description of the reel drive 40A, however, reference is had to a drive element which is common to both reel drives and is in the form of a drive shaft 150 journalled with its ends in suitable bearing brackets on the end castings 24 and 26 of the main frame 22. The shaft 150 carries a sheave 152 which through belts 154 is drivingly connected with any suitable prime mover (not shown).

The reel drive 40A is of belt-type, having to this end a pair of spaced sheaves 156 and 158 over which pass a plurality of belts 160 that drive the sheave 72 on the associated reel stand 36A when the latter is in its winding position (Figs. 1 and 2). The "head" sheave 156 is carried by the drive shaft 150 for infinite axial adjustment thereon into operative alignment with the sheave 72 on the reel stand 36A in any axially adjusted position of the latter, and is in any adjusted position on the shaft 150 locked thereto for rotation therewith through intermedium of a collet 162, for instance, which on tightening and loosening of its associated bolts 164 will act similarly as the described collet 76 (Fig. 3) when its associated bolts 86 are tightened and loosened. The lower or "foot" sheave 158 of the reel drive 40A is rotatably carried in one end of a tension arm 166 the other end of which is pivotally mounted at 168 in the anchor bracket 98. Springs 170, which are suitably anchored with their ends on the anchor bracket 98 and tension arm 166, urge the latter in a direction to tension the belts 160. Thus, the tension arm 166 will straighten the belts 160 when the reel stand 36A is swung into its exchange position, and will yield when the sheave 72 on the stand moves, on the swing of the latter into its winding position, into driving engagement with and deflects the adjacent operating runs 172 of the belts 160 in the fashion shown in Fig. 2.

Since the foot sheave 158 of the reel drive 40A is carried by the anchor bracket 98 in accurate operative alignment with the reel sheave 72 on the stand 36A, and since the anchor bracket and stand are axially adjustable in unison, as described, it follows that the reel sheave 72 and the foot sheave 158 will always remain in accurate operative alignment with each other despite axial adjustments of the stand. This is of considerable advantage in accomplishing axial adjustment of the reel stand 36A and of its associated reel drive 40A, inclusive of accurate alignment of the head sheave 156 of the latter with the foot sheave 158 thereof, for the latter will give an immediate and unmistakable indication of the exact extent of any required axial adjustment of the head sheave 156.

As already mentioned, the reel drive 40B, which is associated with the reel stand 36B, is in all respects identical with the described reel drive 40A. Prominent parts of the reel drive 40B are identified in Fig. 1 by the same reference numerals as their counterparts of the reel drive 40A, except that the suffix "b" is added thereto.

The stock guide 42 (Figs. 1 and 2) is adapted to lead continuous stock *s* in successive layers of orderly turns onto each of the reels R on the stands 36 in their winding positions, and also shift the stock from winding relation with either reel, when fully wound, into winding relation with the other reel, to the end of uninterruptedly winding stock on successive empty reels on their replacement for fully-wound reels on the stands. To this end, the stock guide is axially movably supported on a preferably cylindrical shaft or bar 176 which is mounted with its ends in the opposite end brackets 24 and 26 of the main frame 22 and extends parallel to the frame bars 28 *a-e*, so that the guide may move thereon back and forth within the widthwise confines of either reel R on the stands and lead stock thereonto in successive layers of orderly side-by-side turns until fully wound, and may also move in either direction across the gap *g* between the reels (Fig. 1) in order to bring the stock from winding relation with either reel into winding relation with the other reel. More particularly, the guide 42 comprises slightly spaced rollers 178 between which the stock *s* passes and which are rotatably mounted on and extend forwardly from a carrier 180 that is vertically adjustable mounted at 182, 184 on a bracket 186 which is slidably supported on the bar 176. The guide 42 is moved on the bar 176 as abovementioned, by means of a threaded operating spindle 188, which forms part of the aforementioned guide operating means 44, and with which the guide bracket 186 is in threaded engagement, as at 190 in Fig. 2, so as to be in follower relation therewith and be moved thereby on the bar 176 in opposite directions on rotation of the operating spindle 188 in opposite directions, respectively. The operating spindle 188 is with its opposite ends journaled, in the present instance, in spaced bearing brackets 192 and 194 which are carried by the bar 176 and also secured, as by bolts 196 (Fig. 2), to the frame bar 28*e*. The guide bracket 186 is in back thereof preferably provided with a roller or rollers 198 (Fig. 2) which bear against the frame bar 28*e* and harmlessly transmit to the same any and all counterclockwise thrusts imparted to the guide bracket by the stock *s* on its forced downward draw between the guide rollers 178 onto a driven reel, thereby avoiding any harmful bending stresses in the operating spindle 188 from these operational thrusts of the guide bracket. In order further to protect the operating spindle 188 from clockwise thrusts from the guide bracket 186 (Fig. 2) that may accidentally be imparted to the latter, the guide bracket is also provided with a wear piece 200 which bears against, or is only minutely spaced from, the frame bar 28*e*.

As already mentioned, the stock guide 42 is, for the performance of either of its aforementioned functions of leading stock onto reels on the stands and also from winding relation with either reel into winding relation with the other reel, moved on the bar 176 on rotation of the oper-

ating spindle 188 in opposite directions. Since the stock guide 42 will move on the bar 176 much slower for a reel-winding operation than for crossover of the stock from either reel to the other reel, it stands to reason that the operating spindle 188 will have to be driven at different speeds for these purposes. To this end, the operating spindle 188 may have a slow or "lay-traverse" drive for reel-winding performances of the guide, and a fast or "quick-shift" drive for stock crossover performances of the guide. Since these lay-traverse and quick-shift drives of the operating spindle 188 do not form any part of the present invention, they are not shown, but may be like, or similar to those disclosed in the aforementioned copending application of Nelson et al. These referred-to drives are separate drives, of which the lay-traverse and quick-shift drives may include sprockets 202 and 204 on an extension 206 of the operating spindle 188 for their direct drive of the latter (Fig. 1).

The aforementioned stock severing means 46 comprises 20 a knife blade 210 (Fig. 2) having a cutting edge 212 and being mounted at 214 on an arm 216 which is carried by one end of a stub shaft 218, suitably journaled in a fixed base bracket 220 through which the frame bars 28*a* and 28*b* (see also Fig. 1). The other end of the stub shaft 218 has mounted thereon, as at 222 (Fig. 2), an arm 224 which is pivotally connected at 226 with a clevis 228 on the outer end of a rod 230 of a piston in a cylinder 232. The cylinder 232 is pivotally connected at 234 with an arm 236 which is angularly adjustably mounted at 238 on 30 the frame bar 28*c*. The cylinder 232 is, in the present instance, of the single-acting type, having at its lower end a fluid admission and discharge port in communication with a conventional manually operable "knife" valve (not shown). On manipulating this knife valve to admit fluid 35 under pressure, preferably compressed air, into the cylinder 232, the piston therein will move upwardly and, in consequence, move the knife blade 210, through inter-mediation of the rod 230, arm 224, shaft 218 and arm 216, from the inoperative or retracted position shown in 40 Fig. 2 into an operative or projected position (not shown) in which its cutting edge 212 is in the path of crossover stock between the adjacent stock anchors 48 to be described, and will sever this crossover stock when the same is dragged around with these stock anchors. As soon as 45 the crossover stock is thus severed, the operator releases the aforementioned knife valve, thereby intercepting communication between the cylinder 232 and its source of fluid under pressure and simultaneously permitting discharge of the fluid under pressure from the cylinder, whereupon a preloaded spring 240 between the latter and the clevis 228 on the piston rod 230 acts immediately to 50 retract the knife blade 210 into its inoperative position (Fig. 2).

The apparatus described so far is in all essential respects like that disclosed in the aforementioned copending Nelson et al. application, and does not form any part of the present invention.

In accordance with the present invention, the reels on the stands 36 are provided with the aforementioned stock anchors 48 which are primarily adapted to preclude possibly harmful, and in any event objectionable, snag action of the severed end of the wound stock on each full reel before the same can be brought to a stop. Since the stock anchors 48 are, in the present instance, identical in every respect, only one will be described in detail, namely the anchor 48A which is associated with the reel on the stand 36A (Figs. 1 to 5). To begin with, the anchor 48A is exchangeable on the reel so that it may be used in conjunction with subsequent reels to be placed on the stand 36A for stock winding purposes. To this end, the anchor 48A is, in the present instance, removably mounted on the reel spindle 74 and is releasably coupled to the associated reel. The anchor 48A is in the form of a disc or wheel, having a central hub 242 for its removable mounting on the reel spindle 74 between the adjacent end

flange r' of the reel and the removable end collar 94 on the spindle (Fig. 3). Integrally connected to the hub 242 by a plurality of radial spokes 244 is an annular border 246 which continues as a frusto-conical stock deflector flange 248. The anchor 48A is near its hub 242 provided with a projecting pin 250 which is received in one of the customary coupling apertures 252 in the reel R which is of conventional construction (Fig. 3). Secured to the annular border 246 of the anchor disc 48A, as by rivets 254, for instance, are a plurality of equiangularly spaced brackets 256 providing ledges 258 which together form a stock wind-on rim 260 to which the stock deflector flange 248 leads (Fig. 3). The rim 260 is, in the present instance, of polygonal wind-on outline (Fig. 5), this by virtue of its formation by the sectional ledges 258 on the brackets 256. Outwardly spaced from the ledges 258 on the brackets 256 and joined thereto by connecting webs 261 are lugs or detents 262, respectively, which serve to block any appreciable outward expansion, and hence unwinding, of a stock turn or turns on the wind-on rim 260. To this end, the detents 262 overhang the ledges 258, and hence the wind-on rim 260, not only throughout the width thereof, but therebeyond (Fig. 3) so as to be throughout in obstructing relation with a stock turn or turns on the rim 260 on their natural resilient outward expansion therefrom. While the detents 262 thus overhang or extend over the wind-on rim 260 beyond its entire width, they terminate short of the deflector flange 248 to leave gaps g' therebetween (Fig. 3) through which stock s may pass to the rim 260. Preferably, the detents 262 terminate adjacent portions of the deflector flange 248 which are fairly close to the rim 260 (Fig. 3) so as to have the greater part of the width of this flange available for wind-on of stock without interference from the detents 262. Furthermore, the detents 262 are preferably inclined inwardly toward the deflector flange 248 so that their outer surfaces 264 will serve to deflect stock led thereto onto the flange 248 in order to be deflected or redirected by the latter into winding relation with the rim 260, while their inner surfaces 266 will serve as a shoulder or shoulders which hook-like engage an expanded stock turn or turns and securely hold them against outward escape through the gaps g' to form a snag. The detents 262 are on the inside provided with round-edged ribs 265 for a purpose described hereinafter. The peripheral flange 248 and the outer tapering surfaces 264 of the detents 262 define, in fact, a peripheral track or stock wind-on groove of cross-sectional funnel shape leading to the rim 260 (Fig. 3).

Preferably, the anchor disc 48A is constructed so as to be as light as possible in order to add minimum weight to the already considerable reel load on the off-side spindle 74 and also cause as little aggravation as possible of the usually more or less statically unbalanced condition of the reel load. To this end, all the parts of the anchor disc 48A are preferably made of a light-weight metal in the first place, such as aluminum; for instance, and reinforcing ribs 268 (Figs. 2 and 3) may be resorted to in order to keep wall thickness at a minimum. In addition, the spoke arrangement 244 between the hub 242 and the annular border formation 246 of the anchor disc goes far toward keeping the weight of the latter at a minimum.

As already mentioned, the anchor disc 48B, which is associated with the reel on the stand 36B, is in all respects identical with the described anchor disc 48A. Such prominent parts of the anchor disc 48B as appear in Fig. 1 are identified by the same reference numerals as their counterparts of the anchor disc 48A, save that the suffix "b" is added thereto.

Let it now be assumed that at the beginning of a continuous stock winding operation the guide 42 leads stock s onto the first reel to be wound, for instance the reel R' on the stand 36A (Figs. 1 and 3), in successive layers of orderly side-by-side turns t . The reel R' is then driven,

counterclockwise as viewed in Fig. 2, from the associated drive 40A in the hereinbefore described manner, and the guide 42 is moved back and forth on the frame bar 176 within the widthwise confines of the reel R', the operating spindle 188 of the guide being then operated by the aforementioned lay-traverse drive which includes the sprocket 202 on the spindle extension 206 (Fig. 1). As the reel R' is fully wound with stock, suitable control means (not shown), operated either manually or in any suitable automatic manner, as by a stock measuring device, for instance, will then perform for the first time in the winding operation. Thus, the control means which may be like those disclosed in the aforementioned copending application of Nelson et al., will then perform to render the lay-traverse drive of the guide operating spindle 188 inoperative and simultaneously render operative the aforementioned quick-shift drive thereof which includes the sprocket 204 on the spindle extension 206. As a result thereof, and due to preconditioning of the control means just mentioned, the operating spindle 188 will immediately be driven by the quick-shift drive in a direction to cause quick motion of the guide 42 to the right as viewed in Fig. 1. This change from lay-traverse drive to quick-shift drive of the operating spindle 188 may take place while the guide 42 is anywhere within the confines of the reel R' and may move in either direction. In the exemplary wound condition of the reel R' in Fig. 1, the guide 42 has, at the change from lay-traverse drive to quick-shift drive of its operating spindle 188, proceeded to the left into near approach to the end flange r of the reel, as is evidenced by the last orderly stock turns $t1$ on the reel, and has then reversed and proceeded at the higher speed to the right (Fig. 1), as is evidenced by the few exemplary stock turns $t2$ of considerably larger pitch. The guide 42, in its quick-shift to the right (Fig. 1), crosses the gap g between the full reel R' and the adjacent empty reel R which at that time is also driven from the associated drive 40B. In thus crossing the gap g , the guide 42 brings the stock s into winding relation with the empty reel R, anchoring the stock to the latter near its left-hand end (Fig. 1), in a manner to be described, and then proceeding, on resumption of the operation of its operating spindle 188 by the lay-traverse drive, to lead the stock onto the reel R in successive layers of orderly side-by-side turns and thus resume its normal stock-winding performance on the reel R, the beginning of which is shown in Fig. 1.

When the stock s is thus compelled to cross the gap g between the reels R' and R, a few turns thereof will be come wound on the anchor disc 48A, and also on the adjacent anchor disc 48B, before the stock reaches the empty reel R and becomes anchored thereto. Furthermore, after the stock s has crossed the gap g and become anchored to the empty reel R, the stock extending across the smaller gap between the anchor discs 48A and 48B is severed by the knife 210, all as more fully explained hereinafter. The stock s becomes wound, first on the anchor disc 48A, when the stock, on the described quick-shift of the guide 42, to the right (Fig. 1), crosses the end flange r' of the full reel R' and is by the shifting guide deflected away from the reel flange r' sufficiently to be carried around with the latter. When the stock is thus being carried around with the reel flange r' , the same is crossed over the latter and is then in winding relation with the anchor disc 48A for a brief period, depending on the relative speeds of the driven reel R' and of the quick-shifting guide 42 and also on the adjustment of the guide carrier 180 on the guide bracket 186 in more or less close proximity to the reels R' and R. In any event, as the stock has crossed the end flange r' of the full reel R', the same will first contact the outer surface or surfaces 264 of one or more of the detents 262 on the anchor disc 48A (Figs. 1 and 3) and be cammed or deflected thereby onto the deflector flange 248 thereof which, in turn, cams or deflects the stock into wind-on

relation with the rim 260. The stock thus being led to the rim 260 of the anchor disc 48A will contact the detents 262 thereof only for the briefest period and will almost immediately shift into sole contact with the deflector flange 248 on its continued shift to the right (Fig. 1) by the quick-shifting guide 42, the deflector flange 248 then camming or deflecting more of the stock onto the wind-on rim 260 of the anchor disc 48A so that ordinarily several, more or less, stock turns t_3 are wound on the latter before the stock is, on continued quick progress of the guide 42 to the right, sufficiently deflected away from the flange 248 of the anchor disc 48A to be carried around therewith. As the stock is thus being carried around by the flange 248 of the anchor disc 48A, the stock length between it and the guide 42 intersects the confines of the adjacent anchor disc 48B and, hence, is carried against the deflector flange 248b of the latter (Fig. 1) and cammed thereby into wind-on with the rim 260b thereof to deposit a few, more or less, stock turns t_4 thereon, there then remaining extended between the deflector flanges of both anchor discs a crossover stock length (not shown) which continues to spin around with the latter on the reels R' and R which are driven at the same speeds due to the common drive shaft 150 of the reel drives 40. As the stock is drawn still further to the right by the quick-shifting guide 42, one of the detents 262b of the anchor disc 48B will catch the stock and take it around with it, whereby the stock is deflected over the adjacent end flange r' of the empty reel R and into winding relation with the latter.

Usually, the aforementioned control means for the lay-traverse and quick-shift drives of the guide operating spindle 188 are so arranged that the guide 42 is, at the end of its quick-shift to the right, slightly within the confines of the empty reel R, near or in the position shown in Fig. 1, so as to have wound a few initial stock turns of larger than normal pitch on the empty reel. The control means then act to render the quick-shift drive of the guide-operating spindle 188 inoperative and simultaneously render its lay-traverse drive operative, the guide 42, by preconditioning of the lay-traverse drive, then proceeding at the slower speed to the left as viewed in Fig. 1 to the end flange r' of the empty reel to wind orderly side-by-side stock turns on top of the initially wound stock turns of greater pitch and thus firmly anchor the latter to the empty reel. As the stock s from the guide 42 thus reaches the end flange r' of the empty reel R, the lay-traverse drive of the guide operating spindle 188 reverses in the usual manner so that the guide now proceeds to the right (Fig. 1) for orderly winding of the first full layer of stock on the reel. As the stock reaches the opposite end flange r of the reel, the lay-traverse drive of the guide operating spindle 188 again reverses and the guide 42 will then move in the opposite direction for the deposit of the next full layer of stock on the reel. The lay-traverse drive thus continues to reverse at the proper times until the reel is fully wound.

As soon as the stock s has become anchored to the right reel R (Fig. 1) in the above-described manner, the operator will actuate the aforementioned knife valve in order to cause the piston in the cylinder 232 (Fig. 2) momentarily to project the knife 210 into the path of the crossover stock between the spinning anchor disc 48A and 48B to sever the same. The severed ends e and e' of the wound stock turns t_3 and t_4 on the respective anchor discs 48A and 48B, while in most cases outside the detents 262 and 262b of the latter as shown in Fig. 1, are relatively short and in any event too short to form potentially harmful snags, and these severed stock ends are kept short despite unwinding tendencies of the stock turns on the anchor discs due to their partial elastic recovery from their wound condition. Thus, while partial elastic recovery of the stock turns on the anchor discs 48A and 48B will result in some outward expansion of one or more of these stock turns (Fig. 5), such outward expansion is re-

stricted by the detents 262 which, by their hook-like arrangement (Fig. 3) moreover prevent lateral expansion or escape of the stock turns through the gaps g' between the detents and adjacent stock deflector flanges 248, 5 wherefore these stock turns cannot possibly add to the lengths of their short free severed ends e and e' . Of course, as soon as the crossover stock between the anchor discs 48A and 48B has been severed, as described, the operator will actuate the proper control valve for the 10 cylinder 120 of the stand-operating device 38A (Fig. 2) in order to cause a swing of the reel stand 36A from its illustrated winding position into its reel-exchange position and thereby also cause disengagement of the reel sheave 72 from the associated reel drive 40A, so that the 15 full reel R' will not turn overly long after the crossover stock is severed. After swinging the stand 36A into its exchange position, the end collar 94 on the reel spindle 74 is removed and the collet 76 released (Fig. 3) in order to permit retraction of the spindle from the anchor disc 20 48A and full reel R', whereupon the few stock turns on the anchor disc may readily be removed therefrom through the gaps g' and placed on the full reel. Removal of the stock turns from the anchor disc is facilitated by the aforementioned round-edged ribs 265 on the inside of 25 the detents 262 which help to cam the wound stock toward the gaps g' for their removal therethrough on laterally drawing the stock therefrom. The full reel may then be rolled away and an empty reel rolled in place thereof, whereupon the reel spindle 74 is projected through the 30 empty reel and also through the empty anchor disc 48A which in the meantime has been releasably coupled to the reel, the end collar 94 being then replaced on the reel spindle 74 and the latter shoved to the left (Fig. 3) in order to retain the coupling member 90, the empty reel 35 and the anchor disc 48A in end-to-end engagement and coupled relation with each other, the collet 76 being finally reclamped to lock the reel spindle in place. The operator then actuates the proper valve to cause the stand 36A to be swung into its winding position for the drive of the 40 empty reel thereon so that the latter is ready to receive the crossover stock at the end of the stock winding operation on the reel R on the stand 36B (Fig. 1).

At the end of the stock-winding operation on the reel R on the stand 36B, the aforementioned control means for the lay-traverse and quick-shift drives of the guide-operating spindle 188 again act, in the same manner as described hereinbefore but for motion of the guide 42 in the opposite direction, to cause crossover of the stock from the reel on the stand 36B to the empty reel on the stand 36A and intermittent winding of a few stock turns 50 successively on the anchor discs 48B and 48A, with the stock turns deposited this time on the anchor disc 48B being superposed on the stock turns t_4 deposited thereon on the previous stock crossover from the preceding full reel on the stand 36A to the present reel on the stand 36B. As soon as the stock has at the end of its crossover to the empty reel on the stand 36A been anchored to this empty reel, the crossover stock between the anchor discs 48A and B is severed on actuation of the knife 210, and 55 the operator may then actuate the proper valve to cause the stand 36B to be swung into its reel-exchange position for the exchange of the full reel thereon with an empty reel, and also removal of the initially and finally wound stock turns from the anchor disc 48B and releasable reassembly of the latter with the exchanged empty reel. The 60 stock winding operation of the apparatus thus continues uninterruptedly until the apparatus is stopped or the continuous stock exhausted, the fully-wound reels on the stands being all the while replaced by empty reels and the anchor discs exchanged on the reels, as explained.

It follows from the preceding that during a continuous winding operation of the apparatus the anchor discs 48A and 48B receive both, leading and trailing ends of the stock wound on each reel, except that the anchor disc on the reel first wound in the overall winding operation re-

ceives only a trailing end of the stock wound on this reel. Thus, while in previous continuous winding operations of this type, i.e. without the present anchor discs 48, the trailing ends of the stock on successively wound reels were exposed but the leading ends thereof were buried under the wound stock, the use of the present anchor discs in a continuous winding operation leaves exposed both the leading and trailing ends of the stock on all but the first of the successively wound reels, and this is an important advantage in that it permits certain tests of the stock while the same remains reeled. Thus, if the stock is insulated conductive wire the same may be subjected to the well-known spark test to check it for a possible break while it is wound on a reel, the ready accessibility of the opposite ends of the wound stock being fully adequate for this purpose, as well as for other purposes, such as testing the wound wire for a break in its insulation by the equally well-known water test, for instance.

While the anchor discs 48 in Fig. 1 are shown as having stock wind-on diameters which are only slightly smaller than the maximum stock diameter on the fully-wound reel R' , the wind-on diameters of the anchor discs are preferably quite substantially smaller than the maximum stock diameters on the wound reels if the stock is in a continuous reel winding operation payed-out to the guide 42 from a dancer column, as aforementioned. In that case, the anchor discs are advantageously dimensioned so that their wind-on diameters are substantially midway between the maximum and minimum stock diameters on their associated reels, or are at least considerably smaller and considerably larger than the maximum and minimum stock diameters, respectively, on these reels (Fig. 3). In thus dimensioning the anchor discs respecting their wind-on diameters in relation to the maximum and minimum stock diameters on their associated reels, there is introduced in continuous stock reeling operations a substantially even step-by-step changeover from one extreme wind-on diameter to the other extreme wind-on diameter, i.e. maximum diameter and minimum diameters, with which the stock is confronted on each shift or switch from a fully wound reel to an empty reel. This recurring changeover in substantially even steps from one extreme wind-on diameter to the other extreme wind-on diameter is highly advantageous in continuous stock reeling operations which are under dancer column stock control, for the overall excess stock to be taken up by the dancer column on each stock shift from a full reel to an empty reel is received by the dancer column, not all at once as heretofore, but in intermittent lengths, and more particularly in half-lengths, or near half-lengths, which are taken up by the dancer column, one at a time, with sufficient rapidity to avoid all but momentary stock slackening which in any event is so slight as clearly to preclude any stock entanglement, or entanglement of the stock with parts of the winding apparatus, within or without the dancer column.

While the described releasable assembly of the anchor discs with successive reels to-be-wound is highly advantageous for the reason that only a few, and in fact only two, anchor discs are required for a dual-reel apparatus of the continuous stock winding type while permitting the use of existing reels which are entirely conventional in their construction and require no change whatever for their adaptation to the anchor discs, it is, of course, fully within the purview of the present invention to provide each reel with a fixed anchor disc if this should be desired for any good reason. Thus, Fig. 7 shows a permanently assembled unit 280 of a reel 282 and an anchor disc 284 of which the latter is permanently mounted, as by rivets 286, to the adjacent end flange 288 of the reel 282. The anchor disc 284 may in all respects be like the described anchor disc 48A (Fig. 3), except that the present anchor disc is devoid of a coupling pin and also of a central hub, and is, instead, provided with a mounting boss 290.

Fig. 8 shows an alternative form of a permanently

assembled reel and anchor unit 292 of which the anchor disc 294 is cast in one piece, to the inclusion of the angularly spaced detents 296. Moreover, the stock wind-on rim 298 may be truly cylindrical, this in contrast to the polygonal wind-on outline of the rim 260 of the previously described anchor disc 48A (Fig. 5) which may be preferred for the anchorage of more unwieldy stock by virtue of a lesser tendency of polygonally wound stock to unwind. Also, the detents 296 may, if desired, be a single continuous detent of frusto-conical flange shape, though separate angularly-spaced detents are preferable due to their before-described advantageous catch action on a severed stock end.

Fig. 9 shows part of an anchor disc 300 which may in all respects be like the previously described anchor disc 48A (Fig. 3), except that the wind-on rim 302 of the present anchor disc is cylindrical throughout, being formed in this instance by the periphery of the flanged disc or wheel 304 to which are secured, as by rivets 306, equiangularly spaced brackets 308 which provide the detents 310.

Fig. 10 shows part of an anchor disc 312 which differs from the other described anchor discs by having a wedge action on wound stock for its releasable anchorage thereon. To this end, the instant disc 312 has a peripheral groove 314 of generally V-shaped cross-section which is preferably of a smaller wedge angle at its apex 316. The present anchor disc 312, relying on a wedge action on wound stock for its anchorage thereto, is at best suited for temporary anchorage of more flexible stock which has little elastic recovery tendencies. At that, it may even be advisable to add one or a plurality of angularly spaced detents (not shown) over the wind-on apex 316 of the peripheral groove 314 to catch wound stock if the same should escape from the wind-on apex 316 and tend to unwind.

Figs. 11 and 12 show part of a reel and anchor unit 320 of which the anchor disc 322 is not only releasably coupled to the adjacent end flange 324 of the reel 326 by a coupling pin (not shown), but is also releasably attached thereto, in which case the reel spindle is not required for the releasable support of the anchor disc as in Fig. 3, and the anchor disc may releasably be assembled with the empty reel while off either reel stand of the apparatus (Fig. 1) and both may, as a unit, be placed on either reel stand. To this end, each reel 326 with which the anchor disc 322 is to be associated may have suitably secured to its end flange 324 a ring-shaped mounting boss 328 of L-shaped cross section having in its inwardly extending front leg 330 a plurality of radial slots 332, such as two diametrically opposite slots, for instance, of which one is shown. Adapted to be passed into and from each slot 332 is the shank 334 of a T-shaped lock bolt 336 for bringing its head 338 into and from interlock with the front leg 330 of the mounting boss 328. Each lock bolt 336 may be provided with a follower strap 342 on an eccentric 344 on a stub shaft 346 which is turnable with its ends in spaced lugs 348 on the anchor disc 322. Pinned at 350 to the stub shaft 346 is a handle 352 by means of which to turn the eccentric 344, in one direction to draw the head 338 of the bolt 336 into firm locking engagement with the front leg 330 of the mounting boss 328, and in the opposite direction to retract the bolt head rearwardly therefrom sufficiently for its swing from operative alignment therewith for the release of the anchor disc from the reel, as will be readily understood. The periphery 354 of the mounting boss 328 serves for the accurate location and support of the anchor disc 322 on the reel 326, while the hand-operated lock bolt 336 and its diametrical counterpart on the anchor disc serve releasably to lock the latter to the reel.

The invention may be carried out in other specific ways than those herein set forth without departing from the spirit and essential characteristics of the invention, and the present embodiments are, therefore, to be considered

in all respects as illustrative and not restrictive, and all changes coming within the meaning and equivalency range of the appended claims are intended to be embraced therein.

What is claimed is:

1. In continuous stock winding apparatus, the combination with a pair of spaced reel stands having spindles projecting from their adjacent sides, rotary reels removably mounted on said spindles in spaced end-to-end relation with each other, separate drives connectible with and disconnectible from said reels, respectively, a guide operable to lead flexible stock onto either reel and cross the stock from either reel over to the other reel, and a knife operable to project into the path of crossover stock to sever the same, of stock anchors on and turning with the adjacent ends, respectively, of said reels on opposite sides of the projected knife, each anchor having a peripheral rim, a peripheral track in wind-on relation with crossover stock and arranged to lead wound-on stock onto said rim for its wind thereon, and means engaging the stock on said rim and releasably retaining it on the latter in wound-on fashion after severance of the crossover stock, said track being also arranged to lead the wound-on stock thereon past said stock engaging means.

2. The combination in continuous stock winding apparatus as set forth in claim 1, in which said peripheral rim of each of said anchors is of a diameter approximately halfway between the maximum and minimum stock diameters, respectively, on the reels when fully wound.

3. In continuous stock winding apparatus, the combination with a pair of spaced reel stands having spindles projecting from their adjacent sides, rotary reels removably mounted on said spindles in spaced end-to-end relation with each other, separate drives connectible with and disconnectible from said reels, respectively, a guide operable to lead flexible stock onto either reel and cross the stock from either reel over to the other reel, and a knife operable to project into the path of crossover stock to sever the same, of stock anchors on and turning with the adjacent ends, respectively, of said reels on opposite sides of the projected knife, each of said anchors having a peripheral rim, a shoulder outwardly spaced from and extending over said rim widthwise thereof, and a peripheral track in wind-on relation with crossover stock, of which said track is arranged to lead wound-on stock past said shoulder and onto said rim for its wind thereon, and said shoulder serves releasably to retain the stock on said rim substantially in wound-on fashion after severance of the crossover stock.

4. In continuous stock winding apparatus, the combination with a pair of spaced reel stands having spindles projecting from their adjacent sides, rotary reels removably mounted on said spindles in spaced end-to-end relation with each other, separate drives connectible with and disconnectible from said reels, respectively, a guide operable to lead flexible stock onto either reel and cross the stock from either reel over to the other reel, and a knife operable to project into the path of crossover stock to sever the same, of stock anchors on and turning with the adjacent ends, respectively, of said reels on opposite sides of the projected knife, each of said anchors having a peripheral rim with an outwardly tapering end flange remote from the respective reel forming with said rim in obtuse angle, and a shoulder outwardly spaced from and extending over said rim widthwise thereof, of which said flange serves to cam a wound-on length of crossover stock onto said rim for its wind thereon and said shoulder serves releasably to retain the stock on said rim substantially in wound-on fashion after severance of the crossover stock.

5. The combination in continuous stock winding apparatus as set forth in claim 4, in which said shoulder of each of said anchors extends also over part of said flange widthwise thereof and is spaced therefrom sufficiently to admit stock therebetween.

6. The combination in continuous stock winding apparatus as set forth in claim 4, in which said shoulder of each of said anchors extends circumferentially of said rim and is externally tapered to form with said flange a cross-sectionally funnel-shaped peripheral wind-on groove leading to said rim.

7. The combination in continuous stock winding apparatus as set forth in claim 4, in which said rim is of polygonal wind-on outline.

8. The combination in continuous stock winding apparatus as set forth in claim 4, in which said shoulder is formed in sections arranged circumferentially of said rim in equiangularly spaced fashion.

9. In continuous stock winding apparatus, the combination with a pair of spaced reel stands having spindles projecting from their adjacent sides, rotary reels removably mounted on said spindles in spaced end-to-end relation with each other, separate drives connectible with and disconnectible from said reels, respectively, a guide

10 operable to lead flexible stock onto either reel and cross the stock from either reel over to the other reel, and a knife operable to project into the path of crossover stock to sever the same, of stock anchors on and turning with the adjacent ends, respectively, of said reels on opposite sides of the projected knife, each anchor having a peripheral groove of V-shaped cross section for wind-in of crossover stock in wedged condition in the bottom thereof for its releasable retention therein after severance of the crossover stock.

11. An exchangeable reel unit for stock winding apparatus with a reel drive, comprising a reel adapted to be wound with flexible stock and having opposite end flanges and means for its removable rotary mounting in the apparatus in releasably coupled relation with the reel drive thereof, and a stock anchor having means for its releasable coupling to one of said end flanges on the outside thereof, said anchor having a peripheral rim, a peripheral track adapted to lead stock onto said rim for its wind thereon, and means adapted to engage stock on said rim and releasably retain it on the latter in wound-on fashion, said track being also arranged to lead stock thereon past said stock engaging means.

12. An exchangeable reel unit for stock winding apparatus as set forth in claim 10, in which said reel and anchor have central hubs for their separate removable rotary mounting in the apparatus.

13. A stock anchor, comprising a member having a rotary axis, a wind-on rim on said member about said axis, a peripheral track on said member adapted to lead onto said rim for its wind thereon flexible stock led to said track transversely of said axis, and means adapted to engage stock on said rim and releasably retain it on the latter in wound-on fashion, said track being also arranged to lead stock thereon past said stock engaging means.

14. A stock anchor, comprising a member having a rotary axis, a wind-on rim on said member about said axis, a shoulder on said member outwardly spaced from and extending over said rim widthwise thereof, and a peripheral track on said member, of which said track is arranged to deflect flexible stock led thereto transversely of said axis past said shoulder and into wind-on relation with said rim, and said shoulder is adapted releasably to retain the stock on said rim substantially in wound-on fashion.

15. A stock anchor, comprising a member having a rotary axis, a wind-on rim on said member about said axis, a flange on said member tapering outwardly from one end of said rim and forming with the latter an obtuse angle, and a shoulder on said member outwardly spaced from and extending over said rim widthwise thereof, of which said flange is adapted to cam flexible stock led

thereto transversely of said axis onto said rim for its wind thereon and said shoulder is adapted to block appreciable self-unwinding of the stock from said rim.

16. A stock anchor as set forth in claim 15, in which said shoulder extends also over part of said flange widthwise thereof and is spaced therefrom sufficiently to admit stock therebetween.

17. A stock anchor as set forth in claim 15, in which said shoulder extends circumferentially of said rim and is externally tapered to form with said flange a cross-sectionally funnel-shaped peripheral wind-on groove leading to said rim.

18. A stock anchor as set forth in claim 15, in which said rim is of polygonal wind-on outline.

19. A stock anchor as set forth in claim 15, in which the surface of said shoulder facing said rim is cross-sectionally hook-shaped to gather stock tending to unwind from said rim.

10

20. A stock anchor as set forth in claim 15, in which said shoulder is formed in sections arranged circumferentially of said rim in equiangularly spaced fashion.

21. A stock anchor as set forth in claim 15, in which said shoulder is formed in sections arranged circumferentially of said rim in equiangularly spaced fashion, and said shoulder sections are externally tapered to form with said flange a cross-sectionally funnel-shaped peripheral wind-on groove leading to said rim.
